UNITED STATES PATENT OFFICE

WILLIAM J. PORTER, OF SPOKANE, WASHINGTON

AUTOMOBILE DISPOSAL AND WITHDRAWAL STRUCTURE

Application filed November 14, 1928. Serial No. 319,281.

The object of this invention is to provide a novel form of storage disposal and withdrawal structure for automobiles.

The invention involves opposed banks of 5 superposed floors spaced to form an intervening aisle and each floor being designed to receive cars to be stored, a car carrying platform being movable up and down along said aisle to convey cars to and from storage 10 disposal.

One of the features of the invention is to provide guide rails vertically along the facing edges of the floors, the platform having elongated shoes adapted to be spread into 15 and out of engagement with said rails to retard and arrest the platform.

A feature of the invention resides in means for operating the shoes in such a manner that when the platform is advancing either 20 toward or from a loading position, the shoes will be out of contact with the guide rails, and when it is desired to arrest or retard the platform, and also to hold it in a position of registry with certain of the floors, the 25 shoes will be engaged with the rails for the performance of such functions.

A further feature resides in equipping the platform with a plurality of wheel guiding tracks whereby either a plurality or one car 30 can be carried on said platform in balanced relation therewith, this novel arrangement being so coordinated with the disposition of trackage on the several floors as to permit of the most economical space disposition of 35 such tracks on said floors.

The invention has many other features of novelty which will be more fully described in connection with the accompanying drawings and which will be more particularly 40 pointed out in and by the appended claims.

In the drawings;

Fig. 1, is a vertical sectional view of a storage structure embodying the preferred form of the invention.

Fig. 2, is a sectional view on line 2—2 of Fig. 1, on an enlarged scale.

Fig. 3, is a horizontal sectional view on line 3—3 of Fig. 2.

Fig. 4, is a transverse sectional view on line 4—4 of Fig. 3.

Fig. 5, is a horizontal sectional view on line 5—5 of Fig. 4.

Fig. 6, is a sectional view on line 6—6 of Fig. 7.

Fig. 7, is a vertical sectional view of the 55 parts shown in Fig. 6.

Fig. 8, is an enlarged sectional view of one of the tracks.

Like characters of reference designate 60 similar parts throughout the different figures of the drawings.

This invention is an improvement over that shown in my application filed September 12, 1928, Serial No. 305,433 and in the present case I have shown a housing structure comprising side walls 1 and 2 and roof 3. Near one end, or preferably the front of the housing, I have shown laterally disposed ingress and egress openings 4 and 5 which may be of a width to accommodate two cars, if desired, and through which cars can be run onto and off from the car carrying platform, to be later described, always in a forward direction. The floors 6 and 7, of these 65 ingress and egress openings are preferably not provided with wheel guiding tracks. The bottom central floor portion is shown provided with a recessed clearance way 8, the purpose of which will presently appear.

In the interior of the housing, I provide 70 opposed banks of car storage floors A and B, the floors 9 and 10 of which are in spaced relation to form an intervening aisle C adapted to extend the entire length of the storage structure and throughout the height 75 thereof. Thus, it will be clear that the facing edges 11 and 12, of the banks of superposed car storage floors terminate at the lateral boundaries of the aisle C. I preferably equip 80 each floor 9 and 10 with wheel guiding tracks 13 and 14 which extend toward the edges 11 and 12, but not completely thereto. The outer ends of said tracks may be provided with suitable wheel bumpers 15 and 16, as shown. On top of each bank there is a longitudinally disposed rail 18 and 19 on which the wheels 20 and 21 of a travelling crane 22, are adapted to run. The crane may have 85 traction either by friction or gear and rack connection, as desired, and which is clearly 90 shown.

100

within the skill of the construction engineer.

The tracks 20 and 21 extend the full length of the aisle C and the crane 22 is provided with a suitable motor 23 which may be operatively connected in any desired manner (not shown) to advance the crane in either direction lengthwise of the aisle C. Elevating and lowering cables 24, four in number, are suspended from the crane 22 and the latter is provided with suitable means, such as the motor 23, for paying in and paying out said cables 24 to elevate or lower a car carrying platform 25, to which each cable 24 is suitably connected at a corner of said platform, as clearly shown in Fig. 3. I have shown operating cords 26 to 29, which may be operated to cause horizontal, or vertical movement of said platform. Thus, cord 26, may be used to advance the crane in one direction, cord 27, to cause its advance in another direction, cord 28, to cause ascent and cord 29 to cause descent of the platform 25.

I have shown vertically disposed guide rails 30 and 31 disposed equi-distantly along the facing edges of the floors and said rails may be disposed between each pair of tracks 13 and 14, or in any such adjacency as to enable them to perform their functions.

Reference will next be made to my improved car carrying platform which is more particularly shown in Figs. 2 to 5.

While this platform may be fabricated in any desired manner, I have shown the same having a flat top 32 with depending flanges 33, at its ends, and like depending flanges 34, at its sides. The length of said platform is such as to receive any length of car and the proportions are such that a clearance is afforded between the end flanges 33, and the edges 11 and 12, of the floors 9 and 10, such as will permit movement of said platform amply free from contact with rails 30 and 31, when desired, as will presently appear.

The width of the platform 25, from flanges 34 to 34, is sufficient to accommodate two cars as a maximum capacity, and as will later appear, will also accommodate one car, and in either event, the cars will be in substantially balanced relation on the platform. However, before entering into this phase of the invention, it is desired to point out that with the four supporting cables 24, attached to the corners of the platform 25, and with these cables in such considerable spaced relation, the weight of the platform, either empty or loaded, will have a preponderant tendency to hold the platform against sway in either direction. Thus, it will be clear that the crane 22 can be advanced, after a gentle start, at a rapid rate of travel and the platform can be elevated or lowered even as the crane is advancing the platform along the aisle C.

Reference will next be made to my improved normal service means for coaction with the guide rails 30 and 31.

An operating rock shaft 35 which is shown journalled in pendant bearings 36, hung from the bottom of the platform 25. Arm bosses 37 and 38 are suitably fixed on shaft 35 and each has an upwardly extending arm 39 and 40, respectively, and lower arms 41 and 42, respectively. Operating links 43 and 44 are pivoted to arms 39 and 40, respectively, and like links 45 and 46 are pivoted to the lower arms 41 and 42, respectively, as clearly shown in Figs. 4 and 5. Guiding thrust shafts 47 and 48 are slidably mounted in depending bearings 49 and 50, respectively, which are hung from the platform 25. Links 43 and 44 are pivotally connected with said shafts. Similar shafts 51 and 52 are slidably mounted in bearings 53 and 54, respectively, which are hung from platform 25. An elongated shoe 55, having inwardly bent ends 55', is rigidly mounted on shafts 47 and 48. A similar shoe 56, is rigidly mounted on shafts 51 and 52.

It will thus be seen that when the shaft 35 is rocked in different directions the shoes 55 and 56 will either be contracted away from the rails 30 and 31, respectively, or spread into engagement therewith. I make the shafts 47 and 48, and 51 and 52, of relatively enlarged size so that they will not only function to support and guide the shoes, but they will also be capable of taking the end thrust that may be imposed upon the shoes when the latter function to arrest the platform.

As a means of actuating or rocking shaft 35, I have shown a lever 57, having a boss 58, suitably fixed on shaft 35, said lever extending upwardly through a slot 59, in platform 25. By shifting said lever in either of two directions, the shaft 35 will be rocked to either spread or contract the shoes 55 and 56, as will now be clear. If it is desired to lock the lever 57 in a shoe spreading position, I may employ means such as a wedge block 60, coacting with a portion of slot 59 and said lever, as clearly shown in Fig. 7. Thus, after the lever 35 is locked, the operator will be free to move the cars onto or off from the platform.

I will next describe the means whereby either a plurality or a single car can be run onto or off from the elevating platform and wherein in either event, the car or cars will be in substantially balanced relation to the platform.

Referring more particularly to Figs. 3 and 4, I have shown a pair or set of guide tracks 61, on one side of the longitudinal center of the platform 25, and a set 62, on the opposite side of the longitudinal center thereof. These sets of tracks are employed where two cars are to be loaded onto the platform. A third set of tracks 63 are disposed in intermediate relation to the remaining sets of tracks, as will be seen by reference to the figures noted.

All of said tracks are alike in structure,

and the cross sectional form thereof is clearly shown in Fig. 8, which is drawn to a scale of one quarter of an inch to the foot. Thus it will be seen that these tracks are provided with flanges on opposite sides which are in the form of a gentle "roll" 64, the intermediate portion 65 of which may be flat, or substantially so, thereby embodying the general form of a channel cross section. It is well known that cars have different wheel gages and that in some makes the rear wheels are disposed at a wider or greater gage than the front wheels. At any event, this wide channel way is designed to meet all such variation of gages irrespective of the different sized tires. In practice, the flanges or "rolls" 64, may be one foot apart. Of course these tracks 61, 62 and 63 will be rigidly anchored to the platform in any desired manner.

At each end of each of said tracks, I have provided an extension, and as all are alike in structure and function, only two need be described in detail, reference being had to Fig. 2.

Assuming that the track shown therein is track 63, the ends of which terminate close to the ends of the platform 25, it will be seen that said ends are chamfered at 66 and that an end section or extension section 67, is hinged thereto at 68. Thus, while the platform is being advanced, these end sections are retracted or tilted upwardly, as shown in said figure. However, in loading or unloading a car, said extensions 67 are swung outwardly as shown at the right of Fig. 2, to span the space between the end of the platform and the inner edge of the corresponding floor onto or off from which a car is to be run, and into registry with the floor tracks, 13 or 14, as the case may be. The outer ends of said extensions will rest on the inner edges of the floors 9 or 10, where the tracks 13 and 14 terminate to provide supporting shoulders or spaces.

It will now be clear from reference to Fig. 2, that I have located the shoes 55 and 56 in such novel relation to the platform as to afford a disposition of the extensions 67 in the manner just described.

I will next describe the novelty and importance of the specific location of the tracks on the platform.

The problem presented not only involves accommodation for either a plurality or one car on the platform, but it also involves the accomplishment of this provision without needlessly reducing the storage capacity of the floors 9 and 10. It will be noted that the tracks 13 and 14 are as closely spaced as possible in order to allow for the necessary clearance between adjacent cars. It will also be noted that the tracks on the platform are spaced so as to always bring the two sets of tracks 61 and 62 into registry with two sets of tracks 13 or 14, so that without shifting the platform 25, from the position shown in

Fig. 3, two cars could be simultaneously loaded or unloaded. This results from the fact that the gage of the platform tracks is the same as the gage of the floor tracks. Now three or more sets of tracks, equally spaced, would not only unduly enlarge the side of the platform 25, but it would render it unwieldy in the event that only a single car was to be stored or withdrawn since the cost of such single trip for one car would be equal to a like trip for a plurality of cars. Therefore, by disposing the tracks 63, in an intermediate position, that is, between the outermost tracks 61 and 62, I am enabled with a relatively small size platform, to accommodate either a plurality of cars or a single car.

It will be further noted that when a single car is carried, it will be centrally disposed with respect to the longitudinal axis of the platform whereby a balanced relation is afforded.

Likewise, when two cars are carried, the weight is substantially equally balanced because the cars are equi-distantly disposed on opposite sides of the longitudinal axis of the platform. It will of course be understood that the difference in weight of two cars need not be considered as I am not herein dealing with anything like a precision balanced problem, and the elevating cables 24 are so widely spaced that such difference in weight would not be appreciable, in an apparatus of this kind.

While in practice, it will not usually be done, still, it is clearly possible to load or unload a single car on either set of the plurality of individual sets of tracks 61 or 62, when it is necessary to reach an endmost pair of tracks 13 or 14, that is, such tracks located at an extreme end of the structure. Thus, with the present disposition of interpositioned sets of tracks on the platform, this can be done, and there will only be a minimum of waste space at the end of the structure since the platform can readily reach such endmost tracks with either set of platform tracks 61 or 62.

It will now be clear that while there are clear advantages to the balanced relation feature which has been described, and with this feature utilized, the speed of advance of the platform can be with safety increased, still, the platform is clearly and safely operable with a single car disposed on either tracks 61 or 62, even though a slightly less speed of advance may be desirable in such relatively infrequent uses.

By reference to Fig. 3, it will be noted that the length of the shoes 55 and 56 is such, with respect to the disposition of the guide rails 30 and 31, that said shoes will always be abreast of or in engagement with at least two of such rails on both sides of the intervening aisle, and as shown in Fig. 3, said shoes will

engage three rails, thus insuring safety and ample braking engagement.

When the platform is at any elevation, and at rest, it will of course be held suspended by the crane 22 and cables 24, just as a freight or like elevator, and of course the shoes 55 and 56 would in some measure supplement this anchorage. However, the main function of the shoes is to afford brakage and also to hold the platform securely against sway or any movement from a position of track registry. Thus, the shoes will not only prevent movement of the platform endwise but also sidewise.

In straight vertical ascent or descent, the shoes 55 and 56 will be, in most instances, completely retracted, as shown in Fig. 5. Further, the shoes need not be employed for brakage in such ascent or descent as such movement will be controlled from the crane 22.

However, when the platform is advancing longitudinally of the aisle C, the crane will be gently started and gradually and even quickly increased in its speed and the shoes will be retracted until the platform approaches the selected stall. At this point it is desired to emphasize the fact that with the shoes retracted, there would be, in practice, from six to ten inches free play between the ends of the platform 25 and the rails 30 and 31, although of course this may be varied as required. However, the important fact is that there will be enough freedom of movement of the platform so that the latter can sway ever so slightly, as a body will that is freely suspended, and still not engage said rails 30 and 31. It is by reason of this freedom of said platform that I will, in practice, be able to advance the same so rapidly and with an entire absence of frictional resistance at points below the crane 22. Again, I will assert the importance of the widely spaced cables 24 that greatly aids this character of performance.

In advance of the platform longitudinally of the aisle C, the shoes may be spread into slight or near contact with the rails 30 and 31 and this spreading movement may be increased as the platform approaches registry with the selected floor tracks and finally increased as the position of registry has finally been attained. Thus, the shoes, in addition to the crane, constitute controlling means for the platform. Thus the shoes can be brought into play to retard the platform in any direction of movement of the latter by its actuating means and hence the shoes can act independently of but in general synchronism with said means. After the platform has reached a position of registry, the wedge 60 may be inserted and the lever 57 locked in its adjusted position.

It will now be clear how the platform may be lowered into receiving relation with the in-

gress and egress passage ways 6 and 7, to dispose withdrawn cars in a position for egress from the platform and permit of loading cars onto any of the tracks of the platform. After loading, the platform will be advanced into a registering position with any of the tracks on the floors for disposal purposes. If desired, the tracks on the floors may be omitted, as shown in Fig. 5, and still be within the perimeter of the invention.

It is believed that the invention will be understood from the foregoing description, and while I have herein shown and described one specific form of the invention, I do not wish to be limited thereto except for such limitations as the claims may import.

I claim:

1. In an automobile storage disposal and withdrawal structure, opposed banks of floors spaced to form an intervening aisle therebetween, vertically disposed guide rails on the facing side of said floors, a car carrying platform movable in said aisle diagonally, vertically and horizontally thereof and having elongated shoes, and means for spreading said shoes against said rails to control or arrest said platform or contracting said shoes away from said rails to permit free movement of said platform between said rails.

2. In an automobile storage disposal and withdrawal structure, opposed banks of floors spaced to form an intervening aisle therebetween, vertically disposed guide rails on the facing sides of said floors, a car carrying platform, an overhead crane connected with said platform to advance the latter vertically, horizontally or diagonally in said aisle, elongated shoes for said platform, and means for retracting said shoes while said platform is being advanced and spreading said shoes against said rails to retard or arrest said platform.

3. In an automobile storage disposal and withdrawal structure, opposed banks of superposed floors spaced to form an intervening aisle therebetween, vertically disposed guide rails along the facing edges of said floors, a car carrying platform between said rails and in spaced relation thereto, an overhead crane travelling longitudinally of said aisle, elevating and lowering cables depending from said crane and connected with corner portions of said platform to suspend the latter substantially equi-distantly from said rails while said platform is in motion or at rest, elongated horizontally disposed shoes on said platform for engagement with said rails and means for retracting said shoes away from said rails while said platform is advancing and spreading said shoes against said rails to either retard, arrest, or lock said platform.

4. In an automobile storage disposal and withdrawal structure, opposed banks of

superposed floors spaced to form an intervening aisle therebetween, vertically disposed guide rails on the facing edges of said floors, a car carrying platform between said rails, 5 means for elevating or lowering said platform vertically or diagonally along said aisle and advancing said platform longitudinally thereof, an actuating rock shaft mounted on said car, shoes on said car adapted for engagement with said rails and having guiding thrust shafts, bearings on said platform in which said shafts are longitudinally slideable, said rock shaft having oppositely extending arms, and links pivotally connected 10 with said shafts and arms, whereby said shoes may be retracted from said rails or spread into engagement therewith.

5. In an automobile storage disposal or withdrawal structure, opposed banks of 20 superposed floors spaced to form an intervening aisle therebetween, said floors having car guiding tracks extending toward said aisle, a car carrying platform, means for moving said platform longitudinally and vertically in said aisle, guide rails extending vertically along the facing edges of said floors, shoes on said platform, means for engaging said shoes with said rails to arrest said platform, said platform having two sets 25 of car guiding tracks adapted to register with the tracks of said floors whereby two cars can be carried by said platform in balanced relation, and said platform having a single pair of car guiding tracks disposed 30 in intermediate relation to said pair of tracks whereby a single car can be carried in balanced relation on said platform.

6. In an automobile storage disposal or withdrawal structure, opposed banks of 40 superposed floors spaced to form an intervening aisle therebetween, said floors having car guiding tracks extending toward said aisle and in as closely spaced relation laterally as possible to afford lateral clearance between parallel cars, a car carrying platform movable longitudinally and vertically in said aisle, said platform having a pair of tracks spaced to register with any adjacent tracks of said floors whereby two cars can be carried 45 on said platform and simultaneously unloaded onto a floor with the platform in one position or whereby two cars can be loaded onto said platform from a floor with the platform in one position, and said platform 50 having a single pair of tracks centrally disposed between the outermost of said pair of tracks, whereby a single car can be carried on said platform.

7. In an automobile storage disposal or 60 withdrawal structure, opposed banks of superposed floors spaced to form an intervening aisle therebetween, a car carrying platform movable longitudinally and vertically in said aisle and having a plurality of individual sets of car guiding tracks 65

whereby a plurality of cars can be guided thereby, and said platform having a single set of tracks interpositioned with respect to said first named sets of car guiding tracks whereby a single car can be guided by the latter. 70

In witness whereof, I have hereunto set my hand.

WILLIAM J. PORTER.
